United States Patent Office

Des. 188,037

Patented May 31, 1960

188,037

SHOE

Adolf Dassler, Herzogenaurach, near Nurnberg,
Am Bahnhof, Germany

Filed Apr. 10, 1959, Ser. No. 55,451

Term of patent 14 years

(Cl. D7—7)

I claim:

The ornamental design for a shoe, substantially as shown.
